RAIL-STAY.

1,158,141.

Specification of Letters Patent.

Patented Oct. 26, 1915.

Application filed December 30, 1914. Serial No. 879,710.

To all whom it may concern:

Be it known that I, PHILIP W. MOORE, a citizen of the United States, residing at Evanston, in the county of Cook and State 5 of Illinois, have invented certain new and useful Improvements in Rail-Stays, of which the following is a specification.

My invention relates to a rail stay, that is, to a device for checking the tendency of a 10 railroad rail to creep longitudinally, and the invention consists in the novel improvements, constructions and arrangements which will be hereinafter described and claimed.

The invention contemplates particularly a 15 rail stay of the wedge type, that is, comprising two elements having a wedging relation with respect to each other and the rail, one of which elements bears against the tie and the other stands away from the tie and is 20 driven toward the same so as to give the necessary gripping action.

An important object of the invention is to provide a rail stay of this type in which the free member may be driven toward the tie, 25 in applying the device to the rail, without the twisting or skewing of the parts of the device on the rail which is very likely to occur with many rail stays of the wedge type and which, when it takes place, makes 30 the hold of the device on the rail insecure and ineffectual.

A further object of the invention is to provide a rail stay, of the wedge type, in which the area of contact between the engaging elements and the configuration of the 35 engaging parts of said elements is such as to produce a very considerable friction, resisting the tendency of said elements to become loosened from vibration or other 40 causes.

A further object of the invention is to so construct the elements constituting the device that the free element, that is, the one out of contact with the tie, will be guided 45 on the stationary element, when it is driven into place or moves with the rail, by two separated pairs of wedges in parallel arrangement, whereby a firm grip of the device on the rail is produced which very materially enhances the efficiency of the device 50 in checking the creeping tendency of the rail.

A further object of the invention is to provide a rail stay which will be compact, light, strong, cheap to manufacture, and which 55 may be quickly and conveniently applied to

the rail and removed therefrom when desired.

A further object of the invention is to provide a rail stay comprising a stationary and a movable element having two pairs of 60 coöperating wedge members so disposed that the device may be conveniently applied to a rail which has near it a guard rail so that the amount of free space at the side of the base flange of the rail to which the device 65 is to be applied is considerably restricted; although it will be understood that rail stays constructed in accordance with the invention are not limited in their use to this particular situation.

The drawings appended hereto show the invention embodied in a preferred construction.

Figure 1 is a view, in elevation, showing the rail stay applied to a railroad rail adjacent to which is arranged a guard rail, the rails being illustrated in cross section. Fig. 2 is a sectional plan taken on line 2—2 of Fig. 1. Fig. 3 is a vertical sectional view on line 3—3 of Fig. 2, and Figs. 4 and 5 are 80 perspective views of the two elements constituting the rail stay, certain portions of the element shown in Fig. 5 being broken away so as to better illustrate the construction of this element of the device.

Like characters of reference designate like parts in the several figures of the drawings.

Referring to the drawings, A designates a railroad rail, B one of the cross ties supporting the same, and C a guard rail adjacent rail A, the base flange D of which is cut off on one side in accordance with the usual practice.

The rail stay consists, in the preferred construction shown, of a stationary element 95 E and a movable element F. The stationary element E is provided with a flange or plate G adapted to bear against the tie B and with a jaw H adapted to extend around one edge of the base flange of the rail. This jaw comprises a plate or base member I which bears against the under surface of the base flange of the rail. The movable element F comprises a bar or base member J which extends under and is in contact with 100 the base flange of the rail, a jaw K which engages one edge of said base flange, and a larger jaw L adapted to extend around the jaw H of the stationary member. These two jaws are tapered as shown so that the for- 110

ward movement of the movable element produces a wedging engagement between said elements which tightens their grip on the rail. The engagement between the elements at this end of the device might be effected by other constructions producing a like wedging action when the movable element is driven toward the tie. The base portion of the movable member is cut away 5 at one end so as to provide a recess M to receive the plate or base portion I of the stationary member. The movable member is formed on its under side with a tongue N which projects under and engages a tongue 10 O on the stationary member G. These tongues are formed with coengaging wedging surfaces in parallelism with the wedging surfaces on the jaws H and L.

In applying the device to a rail the stationary member is placed on the rail with its tie abutting flange against one of the cross ties. The other member is then put in place on the rail with its jaw K surrounding one edge of the base flange of said 15 rail and the other jaw L surrounding the jaw H on the first named element. The movable element is then driven toward the tie until a gripping action of the required intimacy is obtained. This will ordinarily be done by striking jaw L with a hammer or maul. If this causes either part of the anchor to twist or skew on the rail base, this 20 may be corrected by striking the driven member on the other end, that is, on the jaw K. The device is an improvement on the wedge type rail stays having a single pair of co-engaging wedge members. In such devices the driven element is accessible 25 only at one end. Hence there is danger that the parts of the device may become twisted 30 in driving up the driven element and the hold on the rail thereby impaired. It will be seen that jaw K, being relatively small, the device may easily be applied to a rail 35 even though there is a guard rail located close thereto. The elements are provided with two pairs of wedge members or faces 40 in parallelism with each other. This circumstance increases the frictional grip of 45 one element on the other so as to minimize the danger of the device being loosened in its grip because of the vibration of the rail, or other causes. Any tendency of the rail 50 to creep is self checked since the forward movement of the rail involves a forward 55 movement of the movable element F and this tightens the lateral grip of the device on the rail base; an effect which is enhanced by the fact that the movable element, guided 60 on the stationary element by the two pairs of coöperating wedge surfaces, is compelled to move forward bodily instead of twisting or rocking as might happen if a single wedge engagement were provided between 65 said elements.

While I have described my invention in a certain preferred embodiment, it will be realized that modifications might be made without departure from the principles of the invention. Therefore I do not wish to 70 be understood as limiting the invention to the precise constructions, arrangements and proportion of parts shown except so far as the claims may be specifically so limited.

I claim:

1. A rail stay comprising a stationary and a movable element which together embrace the base of the rail and are formed so as to provide two pairs of coöperating wedging members, one pair of which is located below the level of the under surface of the base flange of the rail. 75

2. A rail stay comprising a stationary and a movable element which together embrace the base of the rail and are formed so as to provide two pairs of coöperating wedging members, one pair of which is located below the level of the under surface of the base flange of the rail, and the other at one end of the device. 80

3. A rail stay comprising a stationary and a movable element which together embrace the base of the rail and are formed so as to provide two pairs of coöperating wedging members, one pair of which is located under the base flange of the rail approximately in the middle of the same. 85

4. A rail stay comprising a stationary and a movable element which together embrace the base of the rail and are formed so as to provide two pairs of coöperating wedging members, one pair of which is located under the base flange of the rail approximately in the middle of the same and the other at one end of the device. 90

5. A rail stay comprising a stationary and a movable element which together embrace the base flange of the rail and are formed with a pair of jaws, the jaw of one member extending around that of the other, and with a pair of co-engaging wedging tongues. 100

6. A rail stay comprising a stationary and a movable element which together embrace the base flange of the rail and are formed with a pair of jaws, the jaw of one member extending around that of the other, and with a pair of co-engaging wedging tongues located below the level of the under surface of the rail base. 110

7. A rail stay comprising a stationary and a movable element which together embrace the base flange of the rail and are formed with a pair of jaws, the jaw of one member extending around that of the other, and with a pair of co-engaging wedging tongues located under the rail base at approximately the middle thereof. 120

8. A rail stay comprising a stationary and a movable element which together embrace

the base flange of the rail and are formed with a pair of jaws, the jaw of one member extending around that of the other and having a wedging action therewith, and with a pair of co-engaging wedging tongues.

5 9. A rail stay comprising a stationary and a movable element which together embrace the base flange of the rail and are formed with a pair of jaws, the jaw of one member extending around that of the other and having a wedging action therewith, and with a pair of co-engaging wedging tongues located below the level of the under side of the rail base.

10 15. 10. A rail stay comprising a stationary and a movable element which together embrace the base flange of the rail and are formed with a pair of jaws, the jaw of one member extending around that of the other and having a wedging action therewith, and with a pair of co-engaging wedging tongues, located under the rail base at approximately the middle thereof.

15 20. 11. A rail stay comprising a stationary and a movable element formed each with a jaw, which jaws engage opposite edges of the rail base, and one formed with a jaw which extends around the jaw of the other element; said elements being provided additionally with a pair of wedging members below the level of the under surface of the rail base.

25 30. 12. A rail stay comprising a stationary and a movable element formed each with a jaw, which jaws engage opposite edges of the rail base, and one formed with a jaw which extends around the jaw of the other element; said elements being provided additionally with a pair of wedging members under the rail base at approximately the middle thereof.

35 40. 13. A rail stay comprising a stationary and a movable element formed each with a jaw, which jaws engage opposite edges of the rail base, and one formed with a jaw which extends around the jaw of the other element; said elements being provided with a pair of wedging tongues one of which hooks over the other.

45 50. 14. A rail stay comprising a stationary and a movable element formed each with a jaw, which jaws engage opposite edges of the rail base, and one formed with a jaw which extends around the jaw of the other element; said elements being provided with a pair of wedging tongues below the level of the under surface of the rail base, one of which hooks over the other.

55 60. 15. A rail stay comprising a stationary and a movable element formed each with a jaw, which jaws engage opposite edges of the rail base, and one formed with a jaw which extends around the jaw of the other element; said elements being provided with a pair of wedging tongues located under the

65 rail base at approximately the middle thereof, one of which hooks over the other.

70 16. A rail stay comprising an element formed with a tie abutting member and with a jaw which engages one edge of the base flange of the rail, of an element formed at one end with a jaw adapted to engage the opposite edge of the rail base and at the other end with a jaw extending around the jaw of the first named element; said elements being provided additionally with a pair of co-engaging wedging members.

75 80. 17. A rail stay comprising an element formed with a tie abutting member and with a jaw which engages one edge of the base flange of the rail, of an element formed at one end with a jaw adapted to engage the opposite edge of the rail base and at the other end with a jaw extending around the jaw of the first named element; said elements being provided additionally with a pair of co-engaging wedging members located below the level of the under surface of the base flange of the rail.

85 90. 18. A rail stay comprising an element formed with a tie abutting member and with a jaw which engages one edge of the base flange of the rail, of an element formed at one end with a jaw adapted to engage the opposite edge of the rail base and at the other end with a jaw extending around the jaw of the first named element; said elements being provided additionally with a pair of co-engaging wedging members located under the rail base at approximately the middle thereof.

95 100. 19. A rail stay comprising an element formed with a tie abutting member and with a jaw which engages one edge of the base flange of the rail, of an element formed at one end with a jaw adapted to engage the opposite edge of the rail base and at the other end with a jaw extending around the jaw of the first named element and having a base portion extending under the base flange of the rail formed with a recess to receive said first named element.

105 110. 20. A rail stay comprising an element formed with a tie abutting member and with a jaw which engages one edge of the base flange of the rail, of an element formed at one end with a jaw adapted to engage the opposite edge of the rail base and at the other end with a jaw extending around the jaw of the first named element and having a base portion extending under the base flange of the rail formed with a recess to receive said first named element, said elements provided additionally with a pair of co-engaging wedging members.

115 120. 21. A rail stay comprising an element formed with a tie abutting member and with a jaw which engages one edge of the base flange of the rail, of an element formed at one end with a jaw adapted to engage the

opposite edge of the rail base and at the other end with a jaw extending around the jaw of the first named element and having a base portion extending under the base flange 5 of the rail formed with a recess to receive said first named element, said elements provided additionally with a pair of co-engaging wedging members located below the level of the under surface of the base flange of 10 the rail.

22. A rail stay comprising an element formed with a tie abutting member and with a jaw which engages one edge of the base flange of the rail, of an element formed at 15 one end with a jaw adapted to engage the opposite edge of the rail base and at the other end with a jaw extending around the jaw of the first named element and having a base portion extending under the base 20 flange of the rail formed with a recess to receive said first named element, said elements provided additionally with a pair of co-engaging wedging members located under the base flange of the rail at approximately 25 the middle thereof.

23. A rail stay comprising an element formed with a tie abutting member, with a jaw which engages one edge of the base flange of the rail, and with a wedging tongue 30 projecting outwardly toward said jaw, of an element formed at one end with a jaw adapted to engage the opposite edge of the rail base, at the other end with a jaw extending around the jaw of the first named 35 element, and with a laterally projecting tongue which extends under the tongue on the first named element.

24. A rail stay comprising an element formed with a tie abutting member, with a 40 jaw which engages one edge of the base flange of the rail, and with a wedging tongue projecting outwardly toward said jaw, of an element formed at one end with a jaw adapted to engage the opposite edge of the 45 rail base, at the other end with a jaw extending around the jaw of the first named

element, and with a laterally projecting tongue which extends under the tongue on the first named element, said tongues being located below the level of the under surface 50 of said rail base.

25. A rail stay comprising an element formed with a tie abutting member, with a jaw which engages one edge of the base flange of the rail, and with a wedging tongue 55 projecting outwardly toward said jaw, of an element formed at one end with a jaw adapted to engage the opposite edge of the rail base, at the other end with a jaw extending around the jaw of the first named 60 element, and with a laterally projecting tongue which extends under the tongue on the first named element, said tongues being located under said rail base at approximately 65 the middle thereof.

26. A rail stay comprising two elements, one adapted to be abutted against a tie and the other standing free therefrom, said elements being formed with two pairs of co-engaging wedge members in parallel 70 arrangement with respect to each other.

27. A rail stay comprising two elements, one adapted to be abutted against a tie, and the other standing free therefrom, said elements being formed with two pairs 75 of co-engaging wedging members in parallel arrangement with respect to each other, one of said pairs of wedging members being arranged below the level of the under surface of the base flange of the rail.

28. A rail stay comprising two elements, one adapted to be abutted against a tie and the other standing free therefrom, said elements being formed with two pairs of co-engaging wedge members in parallel 80 arrangement with respect to each other, one of said pairs of wedge members being located directly below the base flange of the rail.

PHILIP W. MOORE.
